(57) **CLAIM**

The ornamental design for a hood for automobile, as shown and described.

DESCRIPTION

FIG. 1 is a perspective view of a hood for automobile showing our new design;

FIG. 2 is a front view thereof;

FIG. 3 is a left side view thereof;

FIG. 4 is a right side view thereof; and,

FIG. 5 is a top view thereof.

Bottom view and rear view form no part of the claimed portion of the design.
